[57] CLAIM

The ornamental design for a charcoal starter, as shown and described.

DESCRIPTION

FIG. 1 is a side elevational view of a charcoal starter showing my new design, the opposite side being a mirror image thereof.

FIG. 2 is a top plan view thereof;

FIG. 3 is a bottom plan view thereof; and

FIG. 4 is an exploded front elevational view thereof, shown on a reduced scale, the rear being identical thereto except for the absence of the handle.
